[57] CLAIM

The ornamental design for a sole for a tennis shoe, as shown and described.

DESCRIPTION

FIG. 1 is a perspective view of a sole for a tennis shoe showing my new design, the broken lines showing a tennis shoe upper being for illustrative purposes only and forming no part of the claimed design;

FIG. 2 is a right side elevational view thereof;

FIG. 3 left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The upper surface of the invention understood to be unclaimed subject matter, and the broken lines around the periphery of the surface pattern in FIG. 7 is understood to represent a portion of the surface pattern.
